UNITED STATES PATENT OFFICE.

RALPH BROWN GOODRICH, OF CINCINNATI, OHIO.

HYDRAULIC MOTOR.

No. 884,654.

Specification of Letters Patent.

Patented April 14, 1908.

Application filed October 18, 1907. Serial No. 398,077.

To all whom it may concern:

Be it known that I, RALPH BROWN GOODRICH, a citizen of the United States, residing at Cincinnati, in the county of Hamilton and State of Ohio, have invented certain new and useful Improvements in Hydraulic Motors, of which the following is a specification.

This invention relates to the subject of hydraulic motors, and has special reference to 15 that type of motors known as oscillating motors including in their organization an oscillating piston or vane having an oscillatory or semi-rotary sweep within the cylinder housing the same, and thereby communicating a corresponding motion to the motor or drive shaft.

To this end the invention has in view the provision of certain practical improvements in oscillating motors of the character which 23 are employed for mechanically operating the working elements of washing machines or other light machinery where a motor with an oscillating drive shaft can be utilized.

In this connection, the present invention 25 contemplates a motor of an exceedingly simple, yet thoroughly practical, construction, and in which all of the parts are compactly arranged so as to give a maximum sweep to the operating piston while at the same time 30 securing certainty and positiveness of action in the operation of admitting and exhausting the motor fluid at either side of the oscillating piston.

One of the distinctive objects of the invention 35 is to provide an improved valve equipment for the motor, whereby the valve cage may be constructed economically and accurately. Also, in this connection, the invention provides a novel valve action to not only 40 secure a positive and reliable opening and closing of the valves, but which also entirely obviates lost motion, or the "chattering" which is common to the valve parts of other oscillating motors on the market.

45 As a general object, the invention has in view the improvement of the entire motor from a structural standpoint, including the provision of adequate means for effecting water-tight joints for the cylinder parts 50 without the use of lead or other expensive packing.

With these and many other objects in view, which will more readily appear as the nature of the invention is better understood, 55 the same consists in the novel construction,

combination, and arrangement of parts hereinafter more fully described, illustrated, and claimed.

The essential features of the invention, involved in carrying out the foregoing objects, are necessarily susceptible to structural modification without departing from the scope of the invention, but a preferred embodiment thereof is shown in the accompanying drawings, in which:

Figure 1 is a top plan view of an oscillating motor constructed in accordance with the present invention, showing the upper cylinder head removed to expose the interior parts; the view also indicating the valves held closed by the water pressure exerted in the direction of the dotted line arrow, and the piston moving in the direction of the full line arrow. Fig. 2 is a horizontal sectional view on the line 2--2 of Fig. 3, but illustrating the piston advanced from the position shown in Fig. 1 to a position where the parts are ready to release the inlet valve in the direction indicated by the arrow in Fig. 2. Fig. 3 is a vertical sectional view on the line 3--3 of Fig. 1. Fig. 4 is a detail in perspective of the valve cage, showing the casing plates thereof in separated relation. Fig. 5 is a detail in perspective of one of the valve actuators or actuating springs carried upon each side of the actuating piston. Fig. 6 is a detail sectional view illustrative of the fluid-tight wedge joint provided between the cylinder heads and the edges of the cylinder body so as to dispense with the employment of interposed packing. Fig. 7 is a detail sectional view illustrating the stuffing box construction carried by each cylinder head.

Like references designate corresponding parts in the several figures of the drawings.

The working parts of the improved motor are housed in a circular casing usually termed a motor cylinder. This cylinder is designated in its entirety by the numeral 1, and essentially consists of a circular cylinder body 2 and the upper and lower cylinder heads 3 and 4, respectively. The said upper and lower heads 3 and 4 are usually, and preferably, substantial duplicates in construction, and each of the same consists of a circular casting provided at its edge with a retaining flange 5 overlapping the meeting edge portion of the cylinder body 2, and also provided at its peripheral edge with a plurality of outstanding bolt ears 6 alining with

the corresponding ears of the corresponding head to receive the series of tie bolts 7 arranged about the exterior of the cylinder body providing means for detachably and adjustably clamping the cylinder heads upon the opposite edge portions of the said body 2.

One of the practical improvements of the present invention resides in effecting a fluid-tight joint between the cylinder heads and the cylinder body without the interposition of the expensive lead or equivalent packing which is usually employed, and which kind of packing also frequently frays sufficiently to cause damage to the piston packing, as is well known to those familiar with this class of motors. The improved fluid-tight joint referred to is effected in the present invention by forming the upper and lower edges of the cylinder body 2 with an angular wedge rib 8 having a wedging fit in the correspondingly shaped groove or cleft 9 formed in the inner faces of the heads 3 and 4 contiguous to the retaining flanges 5 thereof. In connection with this detail it is to be noted that the wedging action is caused by having the angle of the ribs 8 of a different degree from the angles of the grooves 9. For instance, the said grooves 9 may be cut in the head castings at an angle of, say 60°, and the ribs 8 formed on the circular wall or body 2 turned to a V at an angle of about 45°. The degree of relative angles of the separate parts can be changed, but the fact of having the elements 8 and 9 cut to V's of different angles, necessarily causes the wider angles of the cylinder body or wall 2 to swage into the narrower angles of the grooves 9, thereby effectually preventing leakage.

In addition to the elements described, each of the cylinder heads 3 and 4 is provided at the center thereof with a stuffing box designated in its entirety by the reference number 10 essentially consisting of the packing cup 11 accommodating therein the shaft packing 12, and interiorly threaded, as at 15, to accommodate the threaded portion of the packing gland 14 carrying at its outer end a wrench head or nut 15. (See Fig. 7.) The shaft packing 12 held in the stuffing boxes 10 of the opposite cylinder heads 3 and 4 is designed to effectually pack the upper and lower portions of the central drive shaft 16, one end portion of which shaft projects outside the motor cylinder or casing, and is designed to be coupled by suitable means to the part or machinery to be driven by the motor, all of which is well understood by those skilled in the art. The central drive shaft 16 is preferably of a hollow formation so as to accommodate therein lubricating grease which finds outlet to the packing of the stuffing boxes through the lubricating holes 17 as suggested in detail Fig. 7 of the drawings.

The opposite stuffing boxes 10 act as the journal bearings for the opposite portions of

the drive shaft 16, and the wall has suitably fitted thereto the oscillating piston 18 having almost a complete circular sweep or semi-rotation within the motor cylinder. This piston preferably consists of a body vane 19, 70 radially arranged with reference to the drive shaft 16 and rigidly secured at its inner end as at 20 to said shaft so as to turn therewith in the operation of the motor.

In addition to the body vane 19 the oscillating piston 18 includes in its construction the side clamp plates 21 arranged respectively upon opposite sides of the vane and serving to clamp in position thereon the side packing sheets 22, which sheets are provided with 80 flange portions 23 contacting with the wall of the cylinder body, upper and lower flange portions 24 contacting respectively with the upper and lower cylinder heads, and flange portions 25 contacting with the drive shaft 85 16 respectively upon opposite side of the connection 20 between the vane 19 and said shaft, thus securing a very effective packing for the piston within its cylinder. The said side clamp plates 21 may be riveted or otherwise rigidly united to the vane 19 and the interposed packing sheets 22, and in addition to performing the functions indicated, the side clamp plates may be utilized as a base upon which are mounted the valve actuators 90 26, one being arranged upon each side of the piston. Each valve actuator essentially consists of a spring body plate riveted or otherwise suitably fastened on the piston, and preferably stamped up from a single blank of 100 sheet metal so as to be formed at opposite edge portions thereof with the normally off-standing valve operating arms 27 and 28, respectively, the functions of which will presently appear.

In connection with what may be termed the upper spring valve operating arm 27 of each of the opposite valve actuators, it is to be observed that the free end of said spring arm is normally sprung away from, but is designed to have a play in front of but against, a laterally deflected lip or flange 29 on the side clamp plate 21, which lip or flange 29 constitutes what may be characterized as a valve releasing abutment and co-operating 110 with the spring arm 27 to start open the inlet valve of the valve equipment of the motor. Referring particularly to this valve equipment of the motor, it is to be noted that the same constitutes one of the practical and important features of the present invention and includes three distinct elements, viz: the valve cage designated in its entirety by the reference number 30, the double or double acting inlet valve designated in its entirety 115 by the reference number 31, and the double or double acting outlet valve designated in its entirety by the reference number 32. It will be observed that the said valve cage 30 is arranged at one side of the axial center of the 120 125 130

cylinder, and hence at one side of the plane of the drive shaft 16, said valve cage being disposed radially with reference to the axis of rotation and extending across the interval 5 between the shaft 16 and one side of the cylinder, and also entirely across the space between the upper and lower cylinder heads 3 and 4.

A feature of importance to note in connection with the valve cage 30 is the fact that the said cage is made out of stamped sheet metal and primarily consists of a pair of duplicate complementary casing plates 33 arranged in opposite parallel matching relation 10 and designed to accommodate the inlet and outlet of the motor fluid, and also to provide for the complete mounting of the inlet and exhaust valves 31 and 32, respectively. The said casing plates 33 of the valve cage are 15 rigidly secured by soldering, brazing, riveting or otherwise, to the wall of the cylinder body, as at 34, and at what may be termed their inner edges, the casing plates 33 are formed with parallel clamping flanges 35 secured together by the fastening means 36 and clamping therebetween the flanged packing strips 37 contacting with the surface of the drive shaft 16 and thereby maintaining a watertight joint between the same and the inner 20 edge of the valve cage.

The duplicate casing plates 33 of the sheet metal valve cage have fitted therebetween at an intermediate point a horizontal partition plate 38 which serves to divide the interior of the valve cage into what may be termed the upper inlet chamber 39 in communication with the supply chest 40 carried by the upper cylinder head; and into the lower outlet chamber 41 in communication 25 with the exhaust chest 42 carried by the lower cylinder head, said two chests 41 and 42 being designed to have suitable pipe connections therewith.

Above the horizontal partition plate 38 30 the opposite casing plates 33 of the valve cage have drawn up therein, with suitable dies, the outwardly facing valve seats 43, and below the plane of the partition 38 the said plates are similarly provided with inwardly 35 facing valve seats 44. It is intended that the said valve seats 43 and 44 are to be finished sufficiently by the forming operation to provide seats for the valves coöoperating therewith, and said valve seats are also preferably of a conical shape to receive correspondingly shaped valve heads. The said outwardly facing valve seats 43 surround what may be termed the inlet ports 45 for the motor cylinder, while the other valve 40 seats 44 surround the outlet ports 46 for the cylinder. The said inlet ports 45 are designed to be covered and uncovered by the opposite spaced and reversely disposed valve heads 47 mounted on a common valve 45 stem 48 so as to provide the said double inlet

valve 31. Likewise, the outlet ports 46 are designed to be covered and uncovered by the opposite spaced and reversely disposed valve heads 49 carried by a common stem 50 and provide the aforesaid double outlet valve 32. Each inlet valve head 47 is preferably provided at the outer side thereof with valve wings 51, while corresponding valve wings 52 are interposed between the heads 49 of the outlet valve heads as will be 70 plainly seen from Fig. 3 of the drawings. The single stem 48 of the inlet valve projects through and beyond both casing plates of the valve cage and lies within the plane of movement of the upper valve operating spring 75 arms 27 of the valve actuators upon opposite sides of the piston, and likewise the stem 50 of the exhaust valve similarly projects beyond the sides of the valve cage and lies within the working plane of the lower spring 80 arm 28 of the valve actuators.

In connection with the relation and operation of parts constituting the improved motor, it is to be noted the fact that the spring valve operating arms 27 and 28 are weaker 85 than the fluid pressure employed in the motor. That is, the said springs are constructed sufficiently weak so as to be weaker than the lowest pressure which will successfully operate the motor, thus insuring the 90 holding of the valves absolutely closed by the fluid pressure at all times and under all conditions except when it is proper for the valve to be opened, thus obviating any lost motion whatever and also obviating the chattering or hammering which is an objection to the valves of oscillating motors. Furthermore, the feature referred to permits the motor to be operated in a practical manner with a wide range of pressures, working equally 95 well whether the water pressure is quite low or quite high.

Referring more particularly to the operation of the parts in connection with the weak springs 27 and 28 above mentioned, it may 100 be assumed in the first instance that the parts occupy the positions shown in Fig. 1. In such positions the fluid is exerting a pressure in the direction of the dotted arrow against the valves, thus holding the inlet and 105 exhaust valve heads at that side of the valve cage respectively open and closed, as plainly shown in Fig. 3 of the drawings, hence permitting the fluid to enter the cylinder from the inlet chamber 39 past the open inlet 110 valve head and exerting pressure against one side of the piston so as to cause the latter to move in the direction of the full line arrow. The piston continues to move in the direction indicated until the upper spring 27 at 115 one side thereof comes in contact with the valve stem at what may be termed the closed side of the valve cage, but as the spring is too weak to overcome the pressure of the fluid, the piston movement continues until the 120

said spring is flexed back against the abutment 29 (as plainly shown in Fig. 2), whereupon the piston starts to open the inlet valve head at the then closed side, with the result of immediately releasing or relieving the pressure at the opposite side of the valve cage, so that both spring arms 27 and 28 come into play and sharply reverse the positions of both valves from the positions shown in Fig. 3, with the consequence of opening up an exhaust for the cylinder on the return sweep of the piston and the opening up of the supply of fluid to impel the piston on such return movement. In this operation, another feature to note is that when the springs 27 and 28 are permitted to come into play, the piston has moved so far that said springs remain under tension after the shifting of the valves so as to hold said valves firmly upon their seats until the pressure has reached the point for starting back the piston. This detail is of importance to prevent the chattering or hammering of the valves.

The operation described repeats itself from side to side of the valve cage as the motor continues to run.

From the foregoing it is thought that the construction, operation, and many advantages of the herein described hydraulic motor will be readily apparent without further description.

I claim:

1. An oscillating motor comprising a cylinder, a radially arranged interior valve cage, separate double acting inlet and outlet valves having stems projecting beyond both sides of the cage, an oscillating piston, and a valve actuator fitted to each side of the piston and consisting of a spring body plate provided at opposite edge portions with normally off-standing spring valve operating arms, and a rigid valve releasing abutment arranged behind and in the path of the free end of the spring arms coöperating with the stem of the double acting inlet valve.

2. An oscillating motor comprising a cylinder, an interior valve cage struck up from

sheet metal, inlet and outlet valves, and an oscillating piston.

3. An oscillating motor comprising a cylinder, an interior valve cage consisting of duplicate casing plates having struck up valve seats, the inlet and outlet valves, and the piston.

4. An oscillating motor comprising a cylinder, an interior valve cage consisting of a pair of duplicate complementary casing plates arranged in spaced relation and provided with paired sets of struck up valve seats, double acting valves coöperating with the valve seats of the cage, and the piston.

5. An oscillating motor comprising a cylinder, an interior valve cage consisting of a pair of duplicate complementary casing plates secured together in spaced relation and formed with paired sets of struck up valve seats, certain of said valve seats being outwardly facing and the others being inwardly facing, a double acting inlet valve consisting of a stem and a pair of reversely arranged valve heads coöperating with one pair of said valve seats, an outlet valve consisting of a valve stem and a pair of valve heads coöperating with the other of said valve seats, and the oscillating piston.

6. An oscillating motor comprising a cylinder, an interior valve cage consisting of a pair of duplicate complementary casing plates secured together in spaced relation and formed with separate sets of inlet and outlet ports, the valve cage also having separated inlet and outlet chambers communicating respectively with the cylinder and said inlet and outlet ports, a double acting inlet valve coöperating with the inlet ports, a double acting outlet valve coöperating with the outlet ports, and a piston carrying valve actuating means.

In testimony whereof I hereunto affix my signature in the presence of two witnesses.

RALPH BROWN GOODRICH.
